CLAIM

The ornamental design for a memory card for an electronic game system, as shown and described.

DESCRIPTION

FIG. 1 is a front elevational view of a memory card for an electronic game system of the present invention;

FIG. 2 is a rear elevational view of a memory card for an electronic game system of FIG. 1;

FIG. 3 is a bottom view of a memory card for an electronic game system of FIG. 1;

FIG. 4 is a top view of a memory card for an electronic game system of FIG. 1;

FIG. 5 is a right side elevational view of a memory card for an electronic game system of FIG. 1;

FIG. 6 is a left side elevational view of a memory card for an electronic game system of FIG. 1; and,

FIG. 7 is a left side perspective view of a memory card for an electronic game system of FIG. 1.

The broken lines in FIGS. 1, 3, 5, 6, and 7 represent ornamental stitching.
